UNITED STATES PATENT OFFICE.

JAMES H. WOODBURY, OF BOSTON, MASSACHUSETTS.

DESIGN FOR A SHOE-TREE OR SIMILAR ARTICLE.

43,076.

Specification for Design.

Patented Sept. 24, 1912.

Application filed May 28, 1912. Serial No. 700,328. Term of patent 14 years.

To all whom it may concern:

Be it known that I, JAMES H. WOODBURY, a citizen of the United States, residing at Boston, in the county of Suffolk and State of Massachusetts, have invented a new, original, and ornamental Design for a Shoe-Tree or Similar Article, of which the following is a specification, reference being had to the accompanying drawings, forming part hereof.

Figure 1 shows a plan view of a shoe

form; Figs. 2 and 3 show side elevations from right and left sides, respectively; and Fig. 4 is an end view looking from the heel end, showing my new design.

I claim:

The ornamental design for a shoe tree or similar article as shown.

JAMES H. WOODBURY.
